CLAIM

The ornamental design for the cooker, as shown and described in the accompanying figures.

DESCRIPTION

FIG. 1 is a front view of a cooker according to a first embodiment of the present invention;

FIG. 2 is side view of the cooker, rotated ninety degrees from the front view of FIG. 1, the opposite side being symmetric thereto;

FIG. 3 is a rear view of the cooker, opposite the front view of FIG. 1; and,

FIG. 4 is a top view of the cooker of FIG. 1; and the broken lines in FIG. 4 illustrate a portion of the cooker that forms no part of the claimed design.

The broken lines identify objects that form no part of the claimed design.
